ESCALATOR

Paul Dennerlein, Stuttgart-Unterturkheim, Germany, assignor to R. Stahl A. G., Stuttgart, Germany

Application September 17, 1934, Serial No. 744,350
In Germany September 20, 1933

9 Claims. (CL. 198—16)

This invention relates to improvements in escalators.

An object of the present invention resides in the provision of an escalator in which the individual step cars can be lightly built and made of light material.

An object of this invention is the provision of an escalator in which the chain wheels, at the points of reversal, are small and have a small diameter.

Another object of this invention is the provision of an escalator in which the step cars run on four rollers which are underneath the platform of the step when in normal position and in which no special guides besides the chain wheels need be provided at the points of reversal for guiding the rollers or step cars.

A further object of the present invention is the provision of an escalator in which a lifting up of the individual step cars is definitely prevented.

Another object of the present invention resides in the provision of an escalator in which no special provisions for adjusting the length of the operating chains need be provided.

A further object of this invention is to provide an escalator in which means are provided on the circulating parts which assure a proper guiding of the step cars at the points of reversal and which make the apparatus independent of slight variations of the length of the operating chains.

An object of the present invention resides in the provision of an escalator in which the operating chains can freely move underneath the step platform.

Another object of this invention is the provision of an escalator in which ample space is available for placing the power plant inside the circulating chain.

A further object of the present invention is to provide an escalator in which the return path of the step cars can have any configuration and can be designed to suit local conditions.

Another object of the present invention is to provide an escalator in which the platforms of the returning step cars are all in one plane and can be cleaned with brushes.

A further object of this invention resides in the provision of an escalator in which stresses caused by the tension of the operation chain at points of change of direction of the chain and acting substantially perpendicular to the direction of the chain are definitely withheld from the step car structures.

Further and other objects of the present in-

vention will be hereinafter set forth in the accompanying specification and claims and shown in the drawings which, by way of illustration, show what I now consider to be a preferred embodiment of my invention.

In the drawings:

Fig. 1 is a diagrammatic side view of an escalator according to my invention.

Fig. 2 is a diagrammatic cross sectional view of an individual step car taken along line 2—2 of Fig. 3.

Fig. 3 is a diagrammatic, longitudinal rear view of a step according to my invention looking in the direction of arrow 3 in Fig. 2.

Fig. 4 is a diagrammatic front view of a step car according to my invention showing chains, counterrollers, and the support of the latter.

Referring more particularly to Fig. 1 of the drawings: 4 represents the carrying chain which is connected to the front axles 19 of the individual step cars 8. The front support rollers 21 of the step car, which are connected to the axles 19, run on the guide rails 9, and the rear support rollers 1 on the guide rail 10. On the ascent of the escalator, guide rails 9 are located higher than guide rails 10. The rails are in one plane and may be united into one rail on the return and the horizontal parts of the escalator. At the points of reversal, chain wheels 13 and 14 are provided. The upper wheel 13 is motor driven, for example, by means of a worm gear 20, an intermediary chain 16, a gear 17, and a motor 15. It must be noted that, with my improved escalator, there is sufficient room to locate the power plant inside the guide rails. According to my invention, the guide rails are interrupted at the points of reversal. The lower or descending rails may have straight ends 11 and 12, whereas the upper or ascending rails have curved ends 18 and 22.

An individual step car is shown in Figs. 2 and 3. It comprises two substantially four-cornered side frames 23 and 24 and the platform 2. Front rollers 21 are mounted on an axle 19 to which the chains 4 and 4' are movably connected. The chain links are provided with upright slots 26 for movably accommodating the axle 19, as is apparent from Fig. 2. The rear rollers 1 are individually mounted to the side frames 23 and 24, and there is no part going across which might hinder the free movement of the chains 4. It must be noted that the rollers, particularly the front rollers to the axle of which the driving chain is connected, are located underneath the platform which renders the structure compact.

and stable. All rollers are in a plane parallel to the plane of the step platform. Small escalators may be provided with only one chain, whereas large and/or wide escalators may have a plurality of chains without necessitating a departure from the basic ideas of my step structure. A lifting-up or tilting of the step cars due to the tension of the chains can be prevented by providing U-shaped guide rails for the front rollers 21, as shown in Fig. 4, in the lower, horizontal parts of the path of the step cars. The individual step cars can be made of light material, since weight is not required for holding the cars down against a lifting effect of the chains, as is possible with other escalator designs.

In order to hold the step cars to the chain and in correct position at the points of reversal, transverse members 7 may be mounted to the chains, the ends of which cooperate with noses 6 projecting from the side frames. In gradually turning into upright position at the lower point of reversal, the transverse members 7 disengage the noses 6; but, before this can happen, the rear rollers 4 engage the curvature 22 of the guide rails 10 which is provided for this purpose. Similar conditions prevail at the upper point of reversal where, upon the movement of the escalator in a descending direction, the curvature 18 catches the rear rollers at the moment the noses 6 disengage the transverse members 7. It is obvious that, with the particular design of my step car, the chain wheels can be of small diameter at the points of reversal. My design further permits to arrange the guide rails, particularly the return rails, to suit any available space conditions and to provide plenty of room for locating the driving motor and gears within the guide rails in contradistinction to other escalator constructions in which the motor is outside of the rails and requires additional space.

Because of the provision of the members 7 cooperating with the noses 6, no adjusting means are required for exactly adjusting the length of the operating chain. A certain amount of lengthening of the chains, which is unavoidable in practical service, does not interfere with the reliable operation of my improved escalator.

It must be further noted that, with an escalator according to the present invention, the platforms 50 of the returning, i. e., hanging step cars are in one plane, and brushes 27 (Fig. 1) may be provided for cleaning the platforms. This is in contradistinction to other escalator designs in which the returning steps form a saw-like surface and 55 can only be cleaned by expensive blower or vacuum plants.

At the point where the ascending part of the escalator changes over to the horizontal part, great pressure may be exerted by the chains on 60 the step car axles, rollers, rails etc. This is particularly true and undesirable in escalators of large dimensions and for great elevations. At these points, I provide a plurality of counter-pressure rollers 28 which support the chain or 65 chains and take up the undesirable pressure. The slots 26, which I mentioned before, in chains 4 prevent pressure vertical to the line of the chain from being exerted on the axles 19 in between the points where the chains are supported 70 by the counterpressure rollers. The rollers 28 may be built as discs with a flat circumference, as shown in Figs. 1 and 4, and are supported by an axle 29 which is supported by the main steel structure 30. If necessary, the elevation of the 75 axles 29 may be made adjustable. This may be

accomplished by providing support pieces 31 having flaps 32 through which the support bolts 33 extend. The support pieces 31 can be screwed to the steel structure 30 at lower or higher elevation by tightening up of nuts 36 at a suitable position. In Fig. 4, a cross section of the guide rails 9 is shown as are provided on the lower horizontal parts of the path of the step cars in order to prevent lifting up of the cars by the tension of the chains.

In order to assure noiseless operation, I propose making the counterpressure rollers not of steel but of some artificial pressed material, for example, that known as Bakelite, fibre or the like.

While I believe the above described embodiments of my invention to be preferred embodiments, I wish it to be understood that I do not desire to be limited to the exact details of design and construction shown and described, for obvious modifications will occur to a person skilled in the art.

What is claimed is:

1. Escalator comprising an endless chain travelling around a loop having a plurality of points where the direction of travel is changed, steps movably attached to said chain and having lateral supporting ends situated outside of said chain, transverse members connected with said chain and situated inside of said supporting ends, abutments connected with said steps and adapted to engage said transverse members when travelling around the points of change of direction of said chain and to thereby prevent that part of the steps to which said abutments are connected from swinging outside of said loop when travelling around the points of change of travel direction.

2. Escalator comprising an endless chain, a plurality of individual step cars, each car having two pairs of support rollers, those two of said support rollers which are in the rear when the car travels upward having an axle in common extending across the car, said axle slidably, movably extending through slots provided in said chain.

3. Escalator comprising an endless carrier travelling around a loop having a plurality of points where the travel direction is changed, steps movably attached to said carrier and having lateral supporting ends between which ends said carrier is situated, means connected to said carrier and situated inside of said supporting ends, means attached to said steps and being independent from and adapted to abuttingly cooperate with said first mentioned means and to prevent that part of said steps to which said second mentioned means are attached from swinging outside of said loop when travelling around the points of change of travel direction.

4. Escalator comprising an endless carrier travelling around a loop having a plurality of points where the travel direction is changed, steps movably attached to said carrier and having lateral supporting ends between which ends said carrier is situated, means connected to said carrier and situated inside of said supporting ends, means attached to said steps and being independent from and adapted to cooperate with said first mentioned means and to prevent that part of said steps to which said second mentioned means are attached from swinging outside of said loop when travelling around the points of change of travel direction.

5. Escalator comprising an endless chain travelling around a plurality of chain wheels, steps movably attached to said chain and having lateral supporting ends between which ends said 5 chain is situated, means connected to and laterally protruding from said chain and situated inside of said supporting ends, means attached to said steps and being independent from and adapted to cooperate with said first mentioned 10 means when travelling around said chain wheels and to prevent that part of said steps to which said second mentioned means are attached from swinging outside of the pitch circle diameter of said chain wheels.

15. Escalator comprising an endless carrier, a plurality of individual step cars of substantially rectangular cross sectional configuration, said carrier being movably connected to said cars substantially at that one of the lower corners 20 of the rectangle which is in the rear when the car travels upwards.

7. Escalator comprising an endless carrier, a plurality of individual step cars having a platform and being provided with a plurality of pairs 25 of rollers located in a plane parallel to said platform, one pair of said rollers being connected with said carrier, means connected with said step cars, and members connected with said carrier and being adapted to engage said 30 means and to prevent that part of said step

cars to which said means are connected from being removed from said carrier at points where the travel direction of said carrier and cars is changed.

8. Escalator comprising an endless carrier, a 5 plurality of individual step cars having a platform and being provided with a plurality of pairs of rollers located in a plane parallel to said platform, one pair of said rollers being connected with said carrier, means connected with said 10 step cars and adjacent to another pair of said rollers, and members connected with said carrier and being adapted to engage said means and to prevent that part of said step cars to which said means are connected from being removed 15 from said carrier at points where the travel direction of said carrier and cars is changed.

9. An escalator having an endless chain comprising links which have elongated openings, the longitudinal axis of which openings extends in a direction which is perpendicular to the travel direction of said chain, a plurality of step cars having members mounted thereon and extending through the openings in said links, whereby said 20 step cars can move relatively to said chain in a direction which is perpendicular to the center line of said chain.
